FREDERICK M. FURBER, OF REVERE, MASSACHUSETTS.

TEMPERATURE-CONTROLLING APPARATUS FOR INTERNAL-COMBUSTION ENGINES.

1,114,246.

Specification of Letters Patent. Patented Oct. 20, 1914.

Application filed March 31, 1914. Serial No. 828,583.

To all whom it may concern:

Be it known that I, FREDERICK M. FURBER, a citizen of the United States, residing at Revere, in the county of Suffolk and State of Massachusetts, have invented certain Improvements in Temperature-Controlling Apparatus for Internal-Combustion Engines, of which the following description, in connection with the accompanying drawings, is a specification, like reference characters on the drawings indicating like parts in the several figures.

The water cooling system of an internal combustion engine for an automobile is usually designed to radiate heat from the engine with sufficient rapidity to maintain the engine at an efficiently operative temperature in warm weather. Consequently, when an automobile is operated in cold weather it is found that the cooling system carries the heat away from the engine so rapidly that its temperature is reduced below the point at which it can operate at its highest efficiency. In severe weather the reduction in temperature produced in this manner is sufficient to make a very noticeable change in the operation of the engine and often is sufficient even to cause the water in the lower part of the radiator to freeze while the engine is running. In order to overcome this difficulty some kind of a covering for part of the radiator is often used in cool weather; but this expedient is unsatisfactory for the reason that the amount of radiator surface required to be covered varies so much with the temperature of the air and with operating conditions that it is impracticable for an operator to control the temperature of his engine properly in this manner.

The present invention has for its primary object to devise means for controlling automatically the rate of radiation of heat by the water cooling system in such a manner as to maintain the engine at substantially all times during its operation at an efficiently operative temperature.

An illustrative embodiment of the invention will now be described, reference being made to the accompanying drawings, in which,

Figure 1 is a perspective of an apparatus constructed in accordance with the invention; Fig. 2 is a longitudinal sectional view of a thermostatic mechanism employed in the apparatus shown in Fig. 1; Fig. 3 is a

cross sectional view showing certain details of construction to which reference will later be made; and Fig. 4 is an end elevation of the parts shown in Fig. 3. Referring to the drawings, 2 indicates an internal combustion engine of a type commonly used in automobiles; 4, the radiator for the engine; and 6 and 8 the pipes that conduct the circulating water or other cooling fluid (hereinafter, for convenience referred to as "water") to and from the radiator. In the arrangement shown the water flows from the engine to the radiator through the pipe 6 and returns to the engine through the pipe 8 after it has been cooled. This arrangement is known as the "thermo siphon" system although the invention is equally applicable to systems in which the circulation of water is produced by other methods.

The mechanism embodying the present invention may constitute a permanent part of the equipment of the engine, or it may be constructed as an attachment, the latter arrangement being shown in the drawings. In this construction a casing 10 is secured to the front of the radiator 4, covering the greater part of the grating or that portion of the radiator through which the air circulates. This casing houses a series of vertical shutters 12, and each shutter has two pivots, one at each end, these pivots being loosely mounted in upper and lower supporting bars 14 and 16, respectively. The casing supports these bars far enough from the front of the radiator so that the shutters may swing from a position in which they are substantially parallel with each other and slightly overlap, as shown in full lines in Figs 1 and 3, to a position at substantially right angles to that just described, as indicated in dotted lines in Fig. 3. Each shutter has a lug 18 projecting therefrom near its lower edge, and these lugs are all pivotally connected to a horizontal bar or link 20 which compels the shutters to open and close together. It will be evident that these shutters obstruct the flow of air through the radiator more or less depending upon their angular position, and this angular position or adjustment of the shutters is controlled by a thermostat which, in turn, is controlled by the temperature of the engine. This thermostat preferably is located in the water cooling system of the engine. In the construction shown the cooling system includes a branch or shunt passage that con-

tains the thermostat. This shunt passage comprises a casing 22 located in a convenient horizontal position beside the engine and closed at one end by a cap 24 and at its opposite end by a casting 26 having an intake nipple 28 and an outlet nipple 30. Water is conducted to the intake 28 by means of a pipe 32, which leads from the pipe 6, and the water is led out of the outlet passage 30 by means of a short pipe 34 that opens into the return pipe 8. Within the casing 22 is mounted a tube 36 of much smaller diameter than the casing, and this tube has one end threaded into a suitable socket in the casting 26 (see Fig. 2) while its opposite end is open so that it communicates with the interior of the casing 22. Consequently, water flowing into the intake 28 of the casing will be obliged to pass through the entire length of the casing and then flow through the tube 36 in order to reach the outlet 30.

The thermostat, which may be of any suitable construction, is mounted inside the tube 36 and, in the form shown, comprises a small tube or stem 38 which is secured to the casting 26 at one end and at its opposite end is provided with a large bulb 40. This bulb is supported in the cap 24 by a nipple 42 that projects from the bulb and enters a corresponding socket formed in the cap. Several spacing blocks, one of which is shown at 44, are inserted between the bulb 40 and the tube 36 to support the tube concentrically on the bulb. The bulb 40 is filled with mercury, or equivalent material. The thermostat also includes a rod 46 which is slidably mounted in the stem 38 with its inner end in contact with the mercury, and its outer end extending out of the tube and through the casting 26 toward the radiator. A spring 48, pressing against a collar 50 fast on the rod 46 and backed up by a nut 52 through which the rod projects and which is threaded into an extension from the casting 26, serves to hold the inner end of the rod pressed against the body of the mercury. The thermostat may conveniently be made of steel, and the parts through which the water circulates, of brass. The rod 46 is connected to the shutter 12 by means of a clamp 54 having a split portion that adjustably grips the rod, and a link 56 having one end pivoted to the clamp and the other end pivoted to a lug 58 that projects from the back of the endmost shutter 12. The casing 22 is provided with a stuffing box to receive a small thermometer 60 which serves to indicate the temperature of the water inside the casing. It will now be evident that, when the engine is running the hot water from the upper part of the jacket will flow to the radiator 4 through the pipe 6, will be cooled in the radiator and will return to the jacket through the pipe 8. Part of this water, however, will

flow from the pipe 6 through the pipe 32 into the casing 22 and will circulate around the thermostat through the tube 36 to the outlet 30 and will return to the engine through the pipes 34 and 8. When the engine is cold and the temperature of the cooling water consequently is low, the mercury in the bulb 40 will be contracted, thus permitting the spring 48 to force the rod 46 inwardly and through the connections 56 and 58 holding the shutters in their closed positions, as shown in Figs. 1 and 3. This, of course, cuts down very materially the flow of air through the radiator and thus decreases very greatly the rate of radiation of heat from the water circulating through the radiator. As the temperature of the engine, and consequently the temperature of the circulating water, rises, the mercury in the bulb 40 will expand, thus forcing the rod 46 outwardly in the stem 38 against the pressure of the spring 48 and causing it to open the shutters 12 more or less, depending upon the rise in temperature. When the engine becomes very warm, the rod 46 will be moved out far enough to turn the shutters 12 into their wide open positions, in which they are shown in dotted lines in Fig. 3, thus permitting a very free circulation of air through the radiator and increasing the rate of radiation to the maximum capacity of the radiator. The thermostat consequently tends to adjust the shutters 12 automatically in such a manner that the temperature of the engine will be allowed to fluctuate only between certain narrow predetermined limits. The adjustability of the clamp 54 on the rod 46 enables the operator to set the apparatus in the manner that he finds most satisfactory for his own engine.

In installing the apparatus and making the original adjustment, the clamp 54 should be loosened so that it will slide freely on the rod 46, and the engine then should be operated with the shutters 12 closed until the temperature of the water has been raised to the point at which the engine is known to operate most efficiently, this temperature being observed on the thermometer 60, or by such other means as the operator may have at hand. The clamp 54 should then be secured to the rod with the link 56 drawn back into the position in which it holds the shutters 12 closed. Any rise in temperature above this point thus will cause the shutters to be opened. It will be evident from Fig. 3 that the connection of the link 56 with the endmost shutter 12 has such a relationship to the pivot of the shutter that a very small movement of the rod will produce a correspondingly greater angular movement of the shutters when the shutters are closed, as shown in full lines in Fig. 3, than when they are partly open. This ar-

arrangement is of advantage since it produces a relatively large opening movement of the shutters upon a very small rise in temperature above the normal temperature and thus tends quickly to restore the normal temperature by the increased radiation that is caused by opening the shutters.

The casing 10 usually need not cover the entire grating of the radiator but preferably should be placed so as to cover the lower part of the radiator since this part contains the cooler water and, therefore, is more likely to freeze.

The apparatus may be detached from the engine whenever desired by removing the bolts that hold the casing 10 on the radiator and disconnecting the pipes 32 and 34 from the engine. The pipe 32 and nipple 30 may be joined to the pipes 6 and 8, respectively, by rubber connectors, if desired, so as to allow for vibration and at the same time facilitate the connection or disconnection of the parts. The casing 22 is detachably mounted on the chassis so that it also may be removed.

Having thus described my invention, what I claim as new and desire to secure by Letters Patent of the United States is:

1. In an automobile, the combination with an internal combustion engine and a water cooling system therefor including a radiator, of means controlled by the temperature of the cooling water for regulating the flow of air through the radiator.

2. In an automobile, the combination with an internal combustion engine and a water cooling system therefor including a radiator, of means adjustable to obstruct more or less the flow of air through the radiator and mechanism for adjusting said means automatically in accordance with the temperature of the water in said system.

3. In an automobile, the combination with an internal combustion engine and a water cooling system therefor including a radiator, of means for controlling the flow of air through the radiator and mechanism for operating said means automatically in accordance with changes in the temperature of the engine and in a manner tending to maintain the temperature of the engine between certain predetermined limits.

4. In an automobile, the combination with an internal combustion engine and a water cooling system therefor including a radiator, of means adjustable to obstruct more or less the flow of air through the radiator and a thermostat responsive to changes in the temperature of the engine for adjusting said

means automatically to increase the flow of air through the radiator as the temperature of the engine rises above a predetermined point and to decrease the flow of air through the radiator as the engine temperature falls below said point.

5. In an automobile, the combination with an internal combustion engine and a water cooling system therefor including a radiator, of means adjustable to obstruct more or less the flow of air through said radiator and a thermostat in said system and connected with said means to adjust it in a manner to cause the flow of air through the radiator to be reduced or increased as the temperature of the cooling water rises above or falls below a predetermined point.

6. In an automobile, the combination with an internal combustion engine and a water cooling system therefor including a radiator, of a series of adjustable shutters arranged to obstruct more or less the flow of air through the radiator depending upon their adjustment, and a thermostat in said cooling system connected with said shutters to adjust them in accordance with changes in the temperature of the water in said system.

7. In an automobile, the combination with an internal combustion engine and a water cooling system therefor including a radiator, of means adjustable to obstruct more or less the flow of air through the radiator, a thermostat in said system, and connections between said thermostat and said means arranged to effect a relatively quick adjustment of said means to increase greatly the circulation of air through the radiator upon a comparatively small rise in the temperature of the water above normal and thereafter to effect a slower adjustment of said means.

8. In an automobile, the combination with an internal combustion engine and a water cooling system therefor including a radiator, of adjustable means detachably secured to the radiator for obstructing more or less the flow of air through the radiator depending upon its adjustment, a thermostat detachably mounted in said system, and means connecting said thermostat with said means to enable the thermostat to adjust said means in accordance with the temperature of the water in said system.

In testimony whereof I have signed my name to this specification in the presence of two subscribing witnesses.
